UNITED STATES PATENT OFFICE.

MAX ARNOLD AND THEODOR ARNDT, OF NEW YORK, N. Y.

PORTABLE BOTTLE WASHER.

Application filed August 23, 1927. Serial No. 214,844.

This invention relates to a new and useful device in the nature of a portable bottle washer, especially adapted for use in the home in as much as our improved device 5 may be readily attached or detached to a water faucet.

The object of the invention is to provide an improved portable bottle washer of novel construction and arrangement of parts, hereinafter more fully described, claimed and illustrated in the accompanying drawing.

Fig. 1 is a fragmentary perspective view of a device of the class mentioned.

Fig. 2 is a fragmentary vertical transverse 15 central sectional view thereof.

Fig. 3 is an enlarged fragmentary view of a portion of Fig. 2, showing the valve in an open position, as same would appear when in use.

20 Fig. 4 is an enlarged vertical transverse central fragmentary sectional view of Fig. 1.

As here embodied our improved device comprises a base member 10, or support of any desired shape, provided with a central lug element 11, extended vertically upwardly therefrom. The tubular member 12 is threadedly attached to the lug element 11, and extends horizontally therefrom. The flexible member 13, preferably a piece of 30 rubber hose, is adapted to slidably engage the tubular member 12 and is secured thereto by means of the usual clamp 14 and the bolt 15, adapted to close the said clamp 14. A clamp 16 engages over the free extremity 35 of the hose 13 and is adapted to slidably engage securely over the spout, or outlet piece of the usual faucet 18, such as ordinarily used in houses for the purpose of supplying running water in kitchen sinks, and the like. 40 The latter described construction is such as will permit my improved device to be easily and readily attached or detached by means of a thumb screw 17.

The tubular member 19 is threadedly 45 attached at its lower extremity to the lug element 11 and extends upwardly therefrom. The cap 20 is threadedly attached to the upper extremity of the tubular member 19 and is provided with a frustum conical 50 shaped upper portion 21 having formed therein a plurality of apertures 22 inclined angularly upwardly. The cap 20 is provided with a central aperture 23 adapted to slidably receive the rod 24 which extends downwardly therefrom inside the tubular member 19. The valve 25 a cylindrical mem-

ber, preferably of rubber, is secured to the lower extremity of the rod 24 by means of the washers 26 and 27 positioned directly above and below the said valve 25. The 60 valve 25 is provided with a tapered outer upper edge 28 normally held in engagement with the tapered lower end of the tubular member 19 by the expansion spring 29, positioned directly below the said valve 25. The 65 rod 24 is extended upwardly somewhat beyond the cap 20 and has secured at its upper extremity a knob 30, preferably of rubber, or any similar soft material.

The above described construction is such 70 as will permit the valve 25 to be opened, as clearly shown in Fig. 3 when a bottle or the like, is placed over the rod 24 which extends inside the said bottle, the said knob 30 engaging or striking the inner bottom of the 75 said bottle, the said bottle forcing the rod 24 downwardly.

A pair of tubular members 32 and 33 are threadedly attached at their lower extremities to the elbow members 34 and 35, respectively, and extended vertically upwardly therefrom. The elbow members 34 and 35 are threadedly attached to the above mentioned lug element 11. Rods 36 and 37, similar to the above mentioned rod 24 are slidably 80 mounted in the said tubular members 32 and 33.

The plungers 38 are slidably mounted, horizontally, in the elbow members 34 and 35, and are provided with tapered extremities 39, normally held in engagement with the said valves 25, by means of the expansion springs 40, positioned intermediate the lug element 11, and the caps 41 secured to the outer extremities of the plungers 38. 90 Suitable packing nuts 42 are threadedly attached to the lug elements 43 of the elbow members 34 and 35, as the usual means of holding the packing 44 in place adjacent to the plungers 38, so as to prevent the leakage 100 of water. The bell cranks 45 are pivotally mounted intermediately thereof, as at 46, by a pin or the like, carried in the brackets 47, attached, as at 47', by bolts, screws, studs or the like to the lug element 11. The bell crank 45 has formed therein an elongated aperture 49 adapted to be slidably engaged by the pin 50 secured to and extended from the plungers 38. The arm 51 is pivotally attached as at 52, by a pin or the like, to the 105 free extremity of the bell crank 45, and is provided with a notched free extremity 53

adapted to engage the brackets 47, as designated by the reference numeral 54, so as to securely hold the plungers 38 in a disengaged position with the valves 25 which are positioned in the elbow members 34 and 35, so as to permit the rods, 36 and 37 to function as above set forth and described, as referred to the said rod 24. It may be readily seen that plunger 38 may be set to lock valve 25 in closed position, or in open position when engaged on top of the valve, or to allow free operation of the valve.

Having thus described our invention, what we claim as new and desire to protect by Letters Patent of the United States is as follows:

1. In a device of the class described, a stationary element, tubular connections including a spring operated valve, a plunger 20 slidably arranged in one of the tubular connections, a spring for normally urging the plunger to latch the valve in open or closed position, a pin secured to and extended from the plunger, a bell-crank pivotally supported 25 intermediate of its ends on the said stationary element, one end thereof being formed with an elongated aperture engaged by the pin, and an arm pivotally attached to the other end of the bell-crank, and having a 30 notched free extremity adapted to engage the stationary element for holding the plunger free from the valve.

2. In a device of the class described, a stationary element, tubular connections in-

cluding a spring operated valve, a plunger 35 slidably arranged in one of the tubular connections, a means for normally urging the plunger to latch the valve in open or closed position, a pin secured to and extended from the plunger, a bell-crank pivotally supported 40 intermediate of its ends on the said stationary element, one end thereof being formed with an elongated aperture engaged by the pin, and an arm pivotally attached to the other end of the bell-crank, and having a notched free extremity adapted to engage the stationary element for holding the plunger free from the valve.

3. In a device of the class described, a stationary element, tubular connections including a spring operated valve, a plunger 50 slidably arranged in one of the tubular connections, a spring for normally urging the plunger to latch the valve in open or closed position, a bell-crank pivotally supported 55 intermediate of its ends on the said stationary element, one end thereof being connected to the plunger for moving the plunger, and an arm pivotally attached to the other end of the bell crank, and having a notched free 60 extremity adapted to engage the stationary element for holding the plunger free from the valve.

In testimony whereof we have affixed our signatures.

MAX ARNOLD:
THEODOR ARNDT.
